[57] CLAIM

The ornamental design for an upper portion of a bottle, as shown and described.

DESCRIPTION

FIG. 1 is a side elevational view of an upper portion of a bottle showing our new ornamental design, the opposite side being a mirror image thereof;

FIG. 2 is a front elevational view thereof;

FIG. 3 is a rear elevational view thereof;

FIG. 4 is a top view thereof;

FIG. 5 is a side elevational view of a modified smaller version of the upper portion of a bottle showing our new design;

FIG. 6 is a front view of the modified version;

FIG. 7 is a rear elevational view of the modified version; and,

FIG. 8 is a top view of the modified version.

The broken lines showing the bottom portion of a bottle and a bottle neck are for illustrative purposes only and do not form part of the claimed design.
